(57) **CLAIM**

The ornamental design for a neuro-electro-therapy headset, as shown.

DESCRIPTION

FIG. 1 is a front elevational view of a neuro-electro-therapy headset, showing my new design.

FIG. 2 is a rear elevational view thereof.

FIG. 3 is a top plan view thereof.

FIG. 4 is a bottom plan view thereof.

FIG. 5 is a left side elevational view thereof.

FIG. 6 is a right side elevational view thereof.

FIG. 7 is an isometric view thereof, taken from the front right side thereof; and,

FIG. 8 is an isometric view thereof, taken from the rear right side thereof.
